UNITED STATES PATENT OFFICE.

BENJAMIN ZIMMER, OF MINNEAPOLIS, MINNESOTA.

TABLE.

1,208,436.

Specification of Letters Patent. Patented Dec. 12, 1916.

Application filed November 11, 1914. Serial No. 871,494.

To all whom it may concern:

Be it known that I, BENJAMIN ZIMMER, citizen of the United States, resident of Minneapolis, county of Hennepin, State of Minnesota, have invented certain new and useful Improvements in Tables, of which the following is a specification.

The object of my invention is to provide a table adapted for use in a library or sitting room, and readily convertible into a table suitable for dining purposes.

A further object is to provide a table that will be neat and ornamental in appearance and of comparatively inexpensive construction.

The invention consists generally in various constructions and combinations, all as hereinafter described and particularly pointed out in the claims.

In the accompanying drawings forming part of this specification, Figure 1 is a plan view, partially in section, with the table top removed, Fig. 2 is a longitudinal sectional view through a table embodying my invention, Fig. 3 is a transverse sectional view taken on the line $x-x$ of Fig. 1, showing the table top in its lowered position, Fig. 4 is a similar view, showing the top in its raised position, Fig. 5 is a transverse sectional view taken on the line $y-y$ of Fig. 1, showing the table top raised and the extended position of the leaves, indicated by dotted lines, Fig. 6 is a similar view, showing the leaves extended and the table top lowered into the plane of the leaves to adapt the table for dining purposes.

In the drawing, 2 represents the side rails of the table, having end rails 3 and supporting legs 4, the table being of the mission type, though the invention can be applied to any style or design of table.

5 and 6 represent cross bars between the rails 2, arranged in pairs in parallel relation, the bars of each pair being spaced 45 apart and the bars 5 having guides 7 thereon for vertically slidable plates 8 upon which the table top 9 is supported and held in position thereon by suitable means, such as dowel pins 10. The plates 8 are preferably arranged at each end of the table near the middle line thereof and have a limited vertical movement through slots 11 provided in the end portions of a plate 12 that extends from end to end of the table along 55 the middle thereof and is secured to the end rails 3 and the cross bars 6 by screws 13

or other suitable means. The end portions of the plate 12 are connected along the middle of the table by a comparatively narrow strip 14 and leaves 15 have their inner edges seated against the longitudinal edges of the plate 12 and are pivotally connected at 16 to one end of the links 17 whose opposite ends are pivotally connected to bars 18 which cross one another and are pivoted at 19 to the strip 14, the links and bars forming a lazy tong construction, for operating the leaves simultaneously, the movement of one leaf in or out causing a similar movement of the opposite leaf.

Each leaf is provided with bars 20 mounted transversely thereof and slidable in slots 21 in the side rails 2 and in the space between the cross bars 5 and 6, the lower edges of these bars having a sliding bearing on the side rails 2 and their upper edges bearing on the under surface of the plate 12 and being guided by these surfaces in the outward and inward movement of the leaves. The inner ends of the bars 20 are provided with 80 depending pins 22 which, when the leaves are drawn out, engage the side rails 2 of the table and limit the outward movement of the leaves. When the leaves are pushed in to contact with the longitudinal edges of the plate 12, the outer edges of the leaves will register with the corresponding edges of the table top as indicated in Fig. 3, the table then presenting the appearance of an ordinary library or sitting room table. When, 90 however, the table top is raised and the leaves are drawn out, the top may be lowered between the leaves, assuming the position indicated in Fig. 6, where the top and the leaves are shown in the same plane, the 95 table being thereby considerably enlarged and made suitable for use as a dining room table. This idea,—first raising the table top and then drawing out the leaves until the top can be lowered between them,—I regard 100 as an important feature of my invention.

For the purpose of raising the table top quickly and conveniently, I provide levers 23, pivoted at a point intermediate to their ends on the cross bars 5, as at 24, and having lugs 25 at their inner ends which fit into sockets 26 in the plates 8. The outer ends of the levers are provided with lugs 27. Arms 28 are pivoted at one end in the cross bars 5 and are connected to one another by 105 suitable means, such as a bail 29, and these arms are provided with lugs 30 which bear

on the outer ends of the leaves 23 and contact with the lugs 27, so that when the arms are rocked by the outward movement of the bail 29, the levers 23 will be tilted to lift the plates 8 and raise the table top. During this outward movement of the bail, the lugs 30 will swing past the pivotal centers of the arms 28 and thereby the bail and levers will be locked and prevented from returning prematurely to their normal position by the weight of the table top or articles which may be placed thereon. When the table top has been lifted, the operator, grasping one of the leaves can, through the connection with the opposite leaf, pull both of the levers outwardly to the position indicated by full lines in Fig. 6. When this has been done, the table top can be lowered between the leaves by swinging the bail inwardly, thereby allowing the top to drop down between the leaves in the same plane thereof, where its upper surface will form a continuation of the leaves and provide a table suitable for dining purposes.

This invention may also be applied to a teawagon or like device, mounted on wheels and capable of movement from place to place. The application of the invention to such a construction would be substantially as shown herein, and I have thought that no further illustration of the specific application would be necessary.

To assist in raising the table top I prefer to provide springs 31 connecting the arms 28 with the side rail 2 and normally under tension when the table top is in its lowered position. These springs can be made of suitable tension to aid the operator materially in swinging the bail from the position shown in Fig. 3 to that illustrated in Fig. 4.

The table can be made in various sizes and designs, and in various ways the details of construction may be modified without departing from the spirit of my invention.

I claim as my invention:

1. A table comprising a frame, a top, vertically movable supports whereon said top is mounted, levers pivotally connected with said supports, a bail pivoted on said frame for operating said levers, and leaves normally under said top and movable outwardly when said top is raised, said top, when lowered, dropping down between said leaves in the plane thereof.

2. A table comprising a frame having cross bars and slides mounted to move vertically on the middle portion of said cross bars and having a limited movement thereon, a table top centrally mounted on said slides, levers pivoted at points intermediate to their ends near said slides and having their inner ends pivotally connected with said slides, the outer ends of said levers extending to a point near the side rails of the table frame, oscillating means mounted in

said frame adjacent to said side rails and having a part for engaging the outer portion of said levers for tilting them to lift said table top and leaves normally fitting beneath said top and adapted to be drawn out 70 when the top is raised, said top, when lowered, dropping down between said leaves in the plane thereof.

3. A table comprising a frame having cross bars and vertical guides thereon near the middle portion of said bars, slides mounted to move vertically in said guides, a table top mounted on said slides, levers pivoted intermediate to their ends adjacent to said guides and having pivotal connections at one end with said slides, the outer ends of said levers being adjacent the side rails of said frame, a rocking means mounted in said frame adjacent said side rails and having means for engagement with said levers, and a depending hand grip portion adjacent the side rails of said frame.

4. The combination, with a table frame, of plates vertically movable therein, a table top mounted on said plates, levers pivotally supported intermediate to their ends on said frame and having pivotal connections with said plates at one end, a bail pivoted on said frame and having means engaging the other ends of said levers for tilting them to raise said plates, and leaves, normally beneath said top and capable when the top is raised of being drawn out to a position in the plane of the top when it is lowered between them.

5. The combination, with a table frame, of levers pivotally supported intermediate to their ends thereon and having lugs at their outer ends, arms pivoted on said frame and having lugs to engage said levers, a bail connecting said arms with one another, the rocking of said bail operating said arms to tilt said levers in a vertical plane, a vertically movable table top, means engaging said top and actuated by the movement of said levers for raising or lowering it, leaves mounted on said frame beneath said top and normally having their edges flush with the corresponding edges of said top, said leaves being movable outwardly when said top is raised, said top, when lowered after the withdrawal of said leaves, fitting between them and in the plane of said leaves.

6. A table comprising a frame, a top, a vertically movable support whereon said top is mounted, a bail pivoted in said frame and operatively connected with said support for raising and lowering it, leaves normally under said top and movable outwardly when said top is raised, said top, when lowered, dropping down between said leaves in 125 the plane thereof.

7. A table comprising a frame, a top, vertically movable supports whereon said top is mounted, levers pivotally connected with said supports, a bail having an eccentric 130

bearing on said levers, leaves normally under said top and movable outwardly when said top is raised, said top, when lowered, dropping down between said leaves in the plane thereof.

8. A table comprising a frame, a top, vertically movable supports whereon said top is mounted, a bail mounted in said frame, means connecting said bail with said supports for raising and lowering them when said bail is operated, leaves normally under said top and movable outwardly when said top is raised, said top when lowered dropping down between said leaves in the plane thereof.

9. A table comprising a frame provided with cross bars, a top, supports for said top

mounted to move vertically in guides on the middle portion of said cross bars, levers pivotally connected with said supports, 20 means having an eccentric bearing on said levers and provided with a hand grip adjacent the side rails of said frame, leaves normally under said top and movable outwardly when said top is raised, said top, 25 when lowered, dropping down between said leaves in the plane thereof.

In witness whereof, I have hereunto set my hand this 7th day of November, 1914.

BENJAMIN ZIMMER.
